UNITED STATES PATENT OFFICE

100,934

DESIGN FOR A FLOWER DISPLAY HOLDER

Hazel I. Artman, St. Louis, Mo.

Application June 1, 1936, Serial No. 62,929

Term of patent 7 years

To all who it may concern:

Be it known that I, Hazel I. Artman, a citizen of the United States, residing at St. Louis, State of Missouri, have invented a new, original, and ornamental Design for a Flower Display Holder, of which the following is a specification, references being had to the accompanying drawing, forming a part hereof.

The figure is a perspective view of a flower display holder, showing my new design.

I claim:

The ornamental design for a flower display holder, as shown.

HAZEL I. ARTMAN.
